(57) **CLAIM**

The ornamental design for modular shelving, as shown and described.

DESCRIPTION

FIG. 1 is a perspective view of a unit of a modular shelving in a first embodiment, showing my new design;

FIG. 2 is a front elevational view thereof;
FIG. 3 is a rear elevational view thereof;
FIG. 4 is a right side elevational view thereof;
FIG. 5 is a left side elevational view thereof;
FIG. 6 is a top plan view thereof;
FIG. 7 is a bottom plan view thereof;
FIG. 8 is a perspective view of a second embodiment of modular shelving;
FIG. 9 is a front elevational view thereof;
FIG. 10 is a rear elevational view thereof;
FIG. 11 is a right side elevational view thereof;
FIG. 12 is a left side elevational view thereof;
FIG. 13 is a top plan view thereof;
FIG. 14 is a bottom plan view thereof;
FIG. 15 is a perspective view of a third embodiment of modular shelving;
FIG. 16 is a front elevational view thereof;
FIG. 17 is a rear elevational view thereof;
FIG. 18 is a right side elevational view thereof;
FIG. 19 is a left side elevational view thereof;
FIG. 20 is a top plan view thereof;
FIG. 21 is a bottom plan view thereof;
FIG. 22 is a perspective view of a fourth embodiment of modular shelving;
FIG. 23 is a front elevational view thereof;
FIG. 24 is a rear elevational view thereof;
FIG. 25 is a right side elevational view thereof;
FIG. 26 is a left side elevational view thereof;
FIG. 27 is a top plan view thereof;
FIG. 28 is a bottom plan view thereof;
FIG. 29 is a perspective view of a fifth embodiment of modular shelving;
FIG. 30 is a front elevational view thereof;
FIG. 31 is a rear elevational view thereof;
FIG. 32 is a right side elevational view thereof;
FIG. 33 is a left side elevational view thereof;
FIG. 34 is a top plan view thereof;
FIG. 35 is a bottom plan view thereof;
FIG. 36 is a perspective view of a sixth embodiment of modular shelving;
FIG. 37 is a front elevational view thereof;
FIG. 38 is a rear elevational view thereof;
FIG. 39 is a right side elevational view thereof;

(Continued)

FIG. 40 is a left side elevational view thereof;
 FIG. 41 is a top plan view thereof;
 FIG. 42 is a bottom plan view thereof;
 FIG. 43 is a perspective view of a seventh embodiment of modular shelving;
 FIG. 44 is a front elevational view thereof;
 FIG. 45 is a rear elevational view thereof;
 FIG. 46 is a right side elevational view thereof;
 FIG. 47 is a left side elevational view thereof;
 FIG. 48 is a top plan view thereof;
 FIG. 49 is a bottom plan view thereof;
 FIG. 50 is a perspective view of an eighth embodiment of modular shelving;
 FIG. 51 is a front elevational view thereof;
 FIG. 52 is a rear elevational view thereof;
 FIG. 53 is a right side elevational view thereof;
 FIG. 54 is a left side elevational view thereof;
 FIG. 55 is a top plan view thereof;
 FIG. 56 is a bottom plan view thereof; and,
 FIG. 57 is a perspective in-use view of the unit of modular shelving.

The broken lines showing in FIG. 57 are for the purposes of illustrating the environment of the article only and form no part of the claimed design.
